US00D766054S

(12) **United States Design Patent** (10) **Patent No.:** **US D766,054 S**
(45) **Date of Patent:** **** Sep. 13, 2016**

(54) **CULTIVATOR**

(71) Applicant: **Fiskars Garden Oy Ab**, Billnäs (FI)

(72) Inventors: **Jouni Salojärvi**, Helsinki (FI); **Mika Sokka**, Tuusula (FI); **Petteri Masalin**, Helsinki (FI); **Heli Säde**, Billanäs (FI)

(73) Assignee: **Fiskars Garden Oy Ab**, Billnäs (FI)

(**) Term: **14 Years**

(21) Appl. No.: **29/511,215**

(22) Filed: **Dec. 8, 2014**

(30) **Foreign Application Priority Data**

Jun. 18, 2014 (EM) 002484923-0004

(51) **LOC (10) Cl.** **08-01**

(52) **U.S. Cl.**

USPC **D8/13**

(58) **Field of Classification Search**

USPC D8/1, 10, 13

CPC A01D 7/06; A01D 7/00; A01D 7/02;

(74) *Attorney, Agent, or Firm* — Foley & Lardner LLP

(57) **CLAIM**

We claim the ornamental design for a cultivator, as shown and described.

DESCRIPTION

FIG. 1 is a top, front perspective view of the claimed design; FIG. 2 is a top, rear perspective view of the claimed design of FIG. 1;

FIG. 3 is another top, rear perspective view of the claimed design of FIG. 1;

FIG. 4 is another top, front perspective view of the claimed design of FIG. 1;

FIG. 5 is a top view of the claimed design of FIG. 1;

FIG. 6 is a right side view of the claimed design of FIG. 1;

FIG. 7 is a bottom, rear perspective view of the claimed design of FIG. 1;

FIG. 8 is a front view of the claimed design of FIG. 1;

FIG. 9 is a left side view of the claimed design of FIG. 1; and,

FIG. 10 is a bottom, front perspective view of the claimed design of FIG. 1.

1 Claim, 10 Drawing Sheets
